UNITED STATES PATENT OFFICE.

WILLIAM C. STEWART, OF SWAMPSOFT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SOLE-FLEXING MACHINE.

1,297,605.

Specification of Letters Patent. Patented Mar. 18, 1919.

Application filed July 26, 1913. Serial No. 781,292.

To all whom it may concern:

Be it known that I, WILLIAM C. STEWART, a subject of the King of Great Britain, residing at Swampscott, in the county of Essex and State of Massachusetts, have invented certain new and useful Improvements in Sole-Flexing Machines; and I do hereby declare the following to be a full, clear, and exact description of the invention, such as will enable others skilled in the art to which it appertains to make and use the same.

The invention relates to sole flexing machines of the type which are constructed and arranged to bend or flex the sole a number of times to impart flexibility thereto.

In the operation of rendering the sole flexible by repeated bending, it is obviously essential that the sole be bent to a considerable extent during the sole flexing operation, so as to exert a considerable strain on the fibers of the stock. Machines of this class as heretofore devised have been constructed to bend the sole to the same extent during each action of the bending means, and since the leather is comparatively stiff and brittle when it is introduced into the machine, the sole is often broken or injured during the first part of the flexing operation.

One object of the invention is to produce a sole flexing machine of the above type in which the sole may be rendered flexible by repeated bending without liability of breaking or injuring the sole. With this object in view, one feature of the invention contemplates the provision of sole bending devices constructed and arranged to increase progressively the extent to which the sole is bent during successive actions of the bending devices. By reason of this construction and arrangement of the bending devices, the sole may be bent to a relatively slight extent during the first part of the flexing operation when it is stiff and brittle and liable to be broken, and the extent of the bending of the sole during each succeeding action of the bending devices may be increased step by step until the desired degree of flexibility has been given to the sole.

Another object of the invention is to produce a simple and efficient sole flexing machine of the type referred to which requires little skill, care or attention on the part of the operator.

Other features of the invention consist of

certain constructions, arrangements and combinations of parts, the advantages of which will be understood by those skilled in the art from the following description.

In the accompanying drawings a machine is illustrated which embodies the various features of the invention in the best form at present known to the inventor, but it is to be understood that except as defined in the claims, the invention is not limited to any particular machine or type of machine, or to any particular construction or arrangement of parts.

In the drawings illustrating a machine embodying the invention in its preferred form, Figure 1 is a front elevation of the upper portion of the machine, with a part of the frame broken away; Fig. 2 is a front elevation of the upper portion of the machine, illustrating certain of the parts in different positions from those in which they appear in Fig. 1; Fig. 3 is a plan of the machine; and Fig. 4 is a side elevation of the lower portion of the machine illustrating particularly the clutch mechanism for connecting the driving shaft with and for disconnecting it from the source of power.

In the illustrated embodiment of the invention, the machine comprises devices for engaging different portions of the detached sole which is to be rendered flexible, and means for relatively moving said devices a number of times in the same direction to impart flexibility thereto. During the sole bending operation the sole is held in operative position relative to the bending devices by suitably actuated gripping jaws. The gripping devices for holding the sole during the sole bending operation comprises a fixed jaw 1 (Figs. 1 and 2) on which the sole rests, formed upon the end of a horizontal arm 2 on the frame of the machine, and a movable jaw 3 formed at the end of the horizontal arm 4 of a bell crank lever 4-6 pivoted on a stud 5 carried by brackets at the rear of the machine frame.

The movable jaw of the gripping device is normally held in open position with relation to the fixed jaw, as illustrated in Fig. 1. To close the jaw 3 on the sole the vertical arm 6 of the bell crank lever 4-6 is connected at its extremity with the inner end of a rod 7 (Fig. 1) which extends through a perforation in a lever 8 pivoted on the

stud 5. A coiled spring 9 surrounds the rod 7 and is interposed between the lever 8 and a thumb nut 10 threaded on the outer end of said rod. The jaw 3 of the gripping device is moved toward and from the jaw 1 by means of a toggle connecting the lower end of the lever 8 with a rock shaft 11 journaled in the frame of the machine. This toggle comprises pivotally connected links 12 and 13, of which the link 12 is pivotally connected with the lower end of the lever 8, and the link 13 is fixed to the shaft 11. When the toggle is broken, as illustrated in Fig. 1, the movable jaw of the gripping device is maintained out of gripping relation with the fixed jaw. When the toggle is straightened, as shown in Fig. 2, the movable jaw of the gripping device is brought down on the sole which has been placed on the jaw 1, and is thereby securely held in operating position. The parts are constructed and arranged so that movement imparted to the movable jaw by the straightening of the toggle is sufficient to grip a sole of minimum thickness between the jaws. In case the sole is of such thickness that the movable jaw of the gripping device engages the sole before the toggle is straightened, the coiled spring 9 yields and permits a relative movement between the lever 8 and the arm 6 of the bell crank lever, and under such a condition the movable jaw of the gripping device is held in yielding engagement with the sole. To operate the toggle, a second arm 14 is fixed to the rock shaft 11 and is connected with the treadle 15 (Fig. 4) by means of the treadle rod 16. A suitably connected spring 17 lifts the treadle rod when the treadle is released. The depression of the treadle will operate to rock the shaft 11 in a direction to straighten the toggle and cause the jaws of the gripping device to grip the sole between them. When the treadle is released and the treadle rod is moved upwardly by the spring 17, the toggle is broken and the movable jaw of the gripping device is moved away from the sole, thus releasing it.

The sole engaging and bending devices comprise a partial cylinder or roll 18 (Figs. 1 to 3) carried at the end of and preferably formed integral with the arm 2. This partial cylinder or roll forms a continuation of the jaw 1, and thus is adapted to engage the lower face of the sole as it lies between the jaws of the gripping device. A second sole engaging device, preferably consisting of a roll 19, is arranged to engage the upper face of the sole as it lies between the gripping jaws, and is mounted for movement about the axis of the partial roll or cylinder 18 to bend the portion of the sole projecting beyond said partial roll away from the plane of the body of the sole. The supporting mechanism for the roll 19 com-

prises a rock shaft 20 journaled in and centrally located with relation to the partial roll 18, having arms 21 and 22 secured to its opposite ends provided at their upper extremities with bearings in which is journaled a shaft 23, on which is carried a frame 24 in which the roll 19 is mounted. The frame 24 is provided with upper arms 25 and 26 (Fig. 3), through which the shaft 23 passes loosely, and with depending arms 27 in which a shaft, carrying the roll 19, is journaled.

During the operation of the machine the shaft 20 is rocked to swing the roll 19 about the partial roll 18. The arms 21 and 22 are provided with stops, one of which is shown at 28 in Fig. 1, and the frame 24 is provided with shoulders 29 opposed to and arranged to be engaged by the stops 28. The frame 24 and the roll 19 carried thereby are normally held in the position illustrated in Fig. 1 with relation to the arms 21 and 22, with the shoulders 29 engaging the stops 28, by means of a coiled spring 30 surrounding the shaft 23 and secured at one extremity to a collar 31 fast to the shaft. The other end of the spring 30 bears upon a portion of the frame 24, as shown in Fig. 3. The spring is normally held under tension by the engagement of a pawl 32 (Fig. 1) pivoted on the arm 21, with one of the teeth of a ratchet wheel 33 secured to the forward end of the shaft 23.

The mechanism for rocking the shaft 20, to swing the roll 19 about the partial roll 18, comprises a gear 34 secured to the forward end of the shaft 20, the teeth of which gear mesh with the teeth of a toothed segment 35 carried upon the end of an arm 36 secured to a rock shaft 37 journaled in the frame of the machine. A second arm 38 is secured to the shaft 37 and is pivotally connected at its free end with a pitman 39 extending from an eccentric strap 40 surrounding an eccentric 41 on the driving shaft 42 of the machine. By means of this mechanism the rotation of the main shaft 42 will oscillate the arm 36, and the segment 35 carried thereby and thus swing the roll 19 back and forth about the partial roll 18.

In operating upon a detached sole, the sole is placed between the jaws of the gripping device with the forward portion of the sole extending to the left (Fig. 1) beyond the partial roll 18. The position of the sole with relation to the sole bending device is determined by a gage 43 against which the heel end of the sole is placed, locating it between the jaws of the gripping device. This gage is arranged to extend over the surface of the table 44 formed by the portion of the frame to the rear of the sole gripping jaws, and is mounted for adjustment toward and from the partial roll 18 so that the distance which the sole pro-

jects beyond said roll when located in bending position may be varied to accommodate soles of varying lengths. In order that the gage 43 may be adjusted in this manner, and 5 securely held in adjusted position, it is provided with a downwardly extending portion which is grooved to receive a rib 45 on the frame of the machine, and is provided with a slot 46 through which a holding screw 47 10 is passed and screwed into the frame. When the sole has been located in bending position with relation to the sole bending devices, the operator depresses the treadle, thereby actuating the movable jaw of the 15 clamping device to grip the sole and hold it during the sole flexing operation. Upon starting the machine the roll 19 will be swung back and forth about the partial roll 18, as previously stated. Fig. 1 illustrates 20 the initial position of the roll 19 with relation to the partial roll 18. When the roll 19 is swung downwardly about the partial roll 18, the roll 19 will engage the portion 25 of the sole projecting beyond the partial roll 18 and bend it about said partial roll, as illustrated in Fig. 2. During the swinging movement of the roll 19 about the partial roll 18, the resistance of the sole to the 30 movement of the roll 19 will overcome the tension of the spring 30 and will, therefore, cause the roll 19 to swing outwardly about the shaft 23 against the tension of the 35 spring. Fig. 2 illustrates in dotted lines the position of the roll 19 during the earlier part of the sole flexing operation, when it has been turned to some extent about the shaft 23 by the resistance of the sole to its pressure.

Each time that the roll 19 is swung about 40 the partial roll 18 the resistance of the sole to the swinging movement of the roll 19 is less than during the previous swinging movement of said roll, because of the increase in the flexibility of the sole, and the 45 roll 19 will swing to a greater extent about the partial roll 18, and bend the sole to a greater degree than during its previous movement (see the two positions of the roll and the sole shown in Fig. 2). The movement 50 of the roll 19 with relation to the roll 18, and the extent to which the sole is bent, therefore increases progressively as the sole flexing operation progresses. During each 55 step in the flexing operation the spring 30 yields before the sole is bent to an extent sufficient to break or injure the sole. The sole is bent to a relatively slight degree during the first part of the flexing operation when it is comparatively stiff and brittle, 60 and step by step the extent to which it is bent in each action of the bending devices is increased until the sole has acquired the desired degree of flexibility. The spring 30 determines the maximum bending force applied 65 to the sole during the sole flexing op-

eration, and this force may be varied to suit the particular sole being operated upon by varying the tension of the spring. This may be accomplished by rotating the shaft 23 in a left-hand direction, Fig. 1, the engagement of the pawl 32 with the ratchet wheel 33 operating to maintain the spring under the tension for which it has been set. 70

In the present invention, mechanism is provided which acts automatically to arrest 75 the relative movement of the sole bending devices when the desired degree of flexibility of the sole has been attained. With this mechanism, after a sole has been introduced into the machine, the machine is 80 started, the sole flexing operation continues until a predetermined degree of flexibility has been imparted to the sole, and the operation of the machine is then arrested, all without requiring any attention on the part 85 of the operator.

The rotation of the main shaft of the machine is controlled by a suitable clutch which is arranged to be engaged to start the machine when the treadle is depressed. The 90 clutch mechanism for the driving shaft (see Fig. 4) comprises a driven clutch member 48 fixed to the driving shaft 42, and a driving clutch member 49 which consists of a pulley arranged for connection with any 95 suitable source of power and provided with a clutch surface which is arranged to engage the opposed clutch surface of the clutch member 48. The pulley 49 is journaled upon a bushing 50 which is loosely mounted 100 on the shaft 42 and is movable longitudinally of the shaft. The outer end of the hub of the pulley 49 is engaged by a dish-shaped cap 51, and the pulley is forced over into 105 clutching engagement with the clutch member 48 by means of coiled springs 52 seated in suitable recesses in a member 53 secured to the end of the shaft 42, the springs engaging an outwardly projecting flange on the cap 51. A brake member 54 is mounted 110 upon the shaft 42 to rotate therewith, but is arranged to slide longitudinally of the shaft into and out of engagement with a fixed brake shoe 55 secured to the frame of the machine. The mechanism for controlling 115 the clutch and brake is so arranged that upon the depression of the treadle the clutch is engaged and the brake is disengaged, and when the treadle is released and is moved upwardly by the spring 17 the 120 clutch will be disengaged and the brake engaged to stop the machine. This controlling mechanism comprises a pin 56 (Fig. 4) mounted in the clutch member 48 to slide in a direction longitudinally of the shaft 42, 125 and provided with a head 57 arranged to engage the inner end of the bushing 50. The pin 56 is held from turning movement in the clutch member 48 in any convenient manner. The inner end of the pin 56 is 130

formed with an inclined face (see Fig. 4), and an arm 58 having a complementary inclined face is fixed to a shaft 59 and arranged so that its upper end may be swung 5 into a position adjacent the shaft 42 and between the brake member 54 and the path of the inner end of the pin 56 (see Fig. 1). When the treadle is depressed to start the machine the arm 58 is swung away from the 10 shaft 42 by the engagement of a forwardly projecting lug 60 (Fig. 1), upon a collar secured to the treadle rod 16, with a laterally projecting lug 61 upon a collar 62 secured to the shaft 59. When the arm 58 is swung 15 away from the shaft 42, the brake member 54 is disengaged from the brake shoe 55 and the pulley 49 is enabled to be moved by the springs 52 into clutching engagement with the clutch member 48. When the treadle is 20 released, and the treadle rod is moved upwardly under the influence of the spring 17, the arm 58 is swung inwardly to bring its upper end between the brake member 54 and the path of the pin 56 by a coiled spring 25 63 (Fig. 1) secured at one end to a fixed point on the machine frame, and at the other connected with an upwardly projecting arm 64 secured to the shaft 59. When the upper end of the arm 58 is swung into a position 30 adjacent the shaft and between the brake member 54 and the path of the pin 56, the rotary movement of the clutch member 48 will bring the inclined end of the pin 56 into engagement with the complementary inclined surface at the end of the arm 58, and the pin 56 will be moved to the right, Fig. 4, through the clutch member 48, thereby forcing the pulley 49 out of clutching engagement with the clutch member 48. The shaft 35 59 is arranged for a slight longitudinal movement in its bearings, and the thrust of the pin 56 against the outer inclined face of the arm 58 will force said arm in a direction to engage the brake member 54 with the 40 brake shoe 55 to stop the machine.

In order that after the machine is started the relative movement of the sole bending devices may continue until the desired degree of flexibility of the sole is attained, and 45 that their movement may then be arrested, means is provided which acts to maintain the engagement of the members of the driving clutch, after the treadle has been depressed to engage said clutch members and 50 start the machine, until a certain degree of flexibility has been imparted to the sole, and which is then actuated to permit the mechanism by which the clutch members are 55 engaged and the brake engaged to act to 60 stop the machine. This means comprises an arm 65 (Figs. 1 and 2) secured to the rock shaft 11 and provided at its end with a recess 66 arranged to receive a roll 67 carried at the end of the arm 68 of a bell crank lever

68-69 pivoted on a stud 70. When the treadle is depressed to start the machine, the arm 66 is lifted and the bell crank lever 68-69 is actuated by a spring 71 to bring the roll 67 beneath the recess at the end of the arm 65. The engagement of the roll 67 70 in said recess will retain the parts of the mechanism for actuating the clutch in position to maintain the clutch members in engagement, and the machine will continue to operate as long as the roll 67 is in engagement with the recess 66. During the sole flexing operation the resistance of the sole to the movement of the roll 19 about the partial roll 18 gradually diminishes as the sole increases in flexibility, and the movement of the roll 19 about the roll 18 increases, since the roll 19 is swung to a less degree about the shaft 23 during each successive movement. A roll 72 (Figs. 2 and 3) is mounted upon the outer end of the 75 shaft upon which the roll 19 is journaled, and the arm 69 of the bell crank lever 68-69 is provided with a curved extremity, as shown in Figs. 1 and 2, which extends into a position to be engaged by the roll 72 80 when the roll 19 reaches a predetermined position in its movements about the roll 18, or when the degree of flexibility of the sole is predetermined by the adjustment of the spring 30 has been attained. Thus, in the 85 illustrated embodiment of the invention, the engagement of the roll 72 with the arm 69 occurs when the resistance of the sole is not sufficient to overcome the pressure of the spring 30. The engagement of the roll 72 90 with the arm 69 will lift this arm and swing the bell crank lever 68-69 in a direction to release the roll 67 from the recess 66. When 95 this occurs, the treadle rod is free to be lifted by the spring 17, and the arm 58 is swung inwardly to a position adjacent the shaft, thereby causing the disengagement of the members of the driving clutch and the engagement of the members of the brake, to 100 stop the machine.

While it is preferred to employ the specific construction and arrangement of the parts shown and described, since this construction and arrangement is the simplest and most efficient embodiment of the invention which has yet been devised, it will be understood that this construction and arrangement is not essential except so far as specified in the claims, and may be varied or modified without departing from the 115 broader features of the invention.

Having explained the nature and object of the invention, and specifically described one form of machine in which it may be embodied, what is claimed is:—

1. A sole flexing machine, having, in combination, means for supporting a sole, and sole bending devices for repeatedly turning

or bending a portion of the sole at an angle to another portion thereof acting to decrease progressively the angle between the said portions of the sole as the operation progresses whereby the extent to which the sole is bent is progressively increased.

2. A sole flexing machine, having, in combination, sole supporting means, and coöperating devices for repeatedly turning or bending one portion of the sole at an angle to another portion thereof, constructed and arranged to increase progressively the extent to which the two portions of the sole are relatively turned or bent as the sole flexing operation progresses.

3. A sole flexing machine, having, in combination, sole supporting means, coöperating devices for repeatedly turning or bending one portion of the sole at an angle to another portion thereof, constructed and arranged to increase progressively the extent to which the two portions of the sole are relatively turned or bent as the sole flexing operation progresses, and means for arresting the sole flexing operation when a predetermined degree of flexibility has been imparted to the sole.

4. A sole flexing machine, having, in combination, sole supporting means, coöperating devices for repeatedly turning or bending one portion of the sole at an angle to another portion thereof, constructed and arranged to increase progressively the extent to which the two portions of the sole are relatively turned or bent as the sole flexing operation progresses, and means for arresting the sole flexing operation when the sole has been bent to a predetermined extent by the bending devices.

40 5. A sole flexing machine, having, in combination, relatively movable sole engaging devices, means for imparting successive relative movements to said devices to bend the sole repeatedly, and means for causing a variation in the relative movement of said devices in successive actions thereof to increase progressively the degree to which the sole is bent as the sole increases in flexibility.

6. A sole flexing machine, having, in combination, relatively movable sole bending devices, means for relatively moving said devices successively to bend the sole repeatedly, means for causing a variation in the relative movement of said devices as the flexing operation progresses to increase progressively the extent to which the sole is bent, and means to arrest the operation of the machine when a predetermined degree of flexibility has been imparted to the sole.

60 7. A sole flexing machine, having, in combination, relatively movable sole engaging devices, means for relatively moving said devices successively to bend the sole repeatedly, and means for causing a progressive

increase in the relative movement of said devices as the sole flexing operation progresses to increase progressively the extent to which the sole is bent.

8. A sole flexing machine, having, in combination, devices for engaging a sole arranged for relative movement to bend the sole, means for successively moving said devices relatively to each other to bend the sole repeatedly, means for causing a progressive increase in the extent of the relative movement of said devices to increase progressively the extent to which the sole is bent as the sole increases in flexibility, and means acting automatically to arrest the operation of the machine when the relative movement of said devices has reached a predetermined extent.

9. A sole flexing machine, having, in combination, sole engaging devices arranged for relative movement to bend the sole, means for successively moving said devices relatively to each other to bend the sole repeatedly, and means for determining the maximum bending force to be applied to the sole by said devices.

10. A sole flexing machine, having, in combination, relatively movable sole engaging devices, means for relatively moving said devices successively to bend the sole repeatedly, and a yielding connection arranged to allow one of said devices to yield to the resistance of the sole during their relative movement.

11. A sole flexing machine, having, in combination, sole engaging devices, means for relatively moving said devices successively to bend the sole repeatedly, a spring to permit one of said devices to yield to the resistance of the sole during their relative movement and thereby cause a progressive increase in the extent to which the sole is bent as the sole increases in flexibility, and means acting automatically to arrest the operation of the machine when the sole is bent to a predetermined extent by said devices.

12. A sole flexing machine, having, in combination, relatively movable sole engaging devices, means for relatively moving said devices to bend the sole, a spring arranged to permit one of said devices to yield to the resistance of the sole during the relative movement of said devices, and means whereby the tension of the spring may be adjusted.

13. A sole flexing machine, having, in combination, a sole engaging member having a convex face, means for holding the sole in position with one face thereof resting on said member, and with a portion thereof projecting freely beyond said member, a device for engaging the portion of the sole beyond said member, and means for moving said device successively with relation to said

member to bend the free projecting portion of the sole repeatedly about the convex face of said member.

14. A sole flexing machine, having, in combination, a sole engaging member, means for holding the sole in position with one face thereof resting on said member, and with a portion thereof projecting freely beyond said member, a device for engaging the free projecting portion of the sole, means for moving said device successively with relation to said member to bend the free projecting portion of the sole repeatedly at an angle to the plane of the other portion thereof, and a spring support for said device arranged to allow said device to yield to the resistance of the sole during its movement with relation to said member.

15. A sole flexing machine, having, in combination, a roll, means for supporting a sole with one face thereof resting on the roll, and with a portion thereof projecting freely beyond the roll, a shaft arranged coaxially with the roll, a device for engaging the free projecting portion of the sole supported on said shaft, and means for moving said device successively about the axis of the roll to bend the portion of the sole engaged thereby repeatedly about the roll, comprising a gear fast on said shaft, a gear segment meshing with said gear, and means for oscillating said gear segment.

16. A sole flexing machine, having in combination, relatively movable sole engaging devices, means for relatively moving said devices to bend the sole, a spring arranged to permit one of said devices to yield to the

resistance of the sole during the relative movement of said devices, a tripping member moving with the latter device, a trip lever arranged to be actuated by the tripping member when a predetermined degree of flexibility has been imparted to the sole, and means controlled by the trip lever for arresting the operation of the machine when the trip lever is actuated by the tripping member.

17. A sole flexing machine, having in combination, a sole engaging member having a convex face, means for holding the sole in position with one face thereof resting on said member and with a portion thereof projecting freely beyond said member, a device for engaging the portion of the sole projecting beyond said member pivoted to swing about the convex face of said member, means for swinging said device successively about the convex face of said member to bend the sole repeatedly, a spring arranged to permit said device to yield to the resistance of the sole during its sole bending movement, a tripping member mounted to move with said device, a trip lever arranged to be actuated by said tripping member when a predetermined degree of flexibility has been imparted to the sole, and means controlled by the trip lever for arresting the operation of the machine when the trip lever is actuated by the tripping member.
